CLAIM

The ornamental design for a dining chair, as shown and described.

DESCRIPTION

FIG. 1 is a perspective view of a dining chair showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The dash-dash broken lines depict portions of the dining chair that form no part of the claimed design. The dotted lines illustrate boundaries of the claimed design and form no part thereof.

1 Claim, 7 Drawing Sheets
